BUILDING SLAB

Filed Nov. 26, 1928

UNITED STATES PATENT OFFICE

JOHN H. POWERS, OF KANSAS CITY, KANSAS; MARY A. POWERS OWNER BY DECREE OF COURT

BUILDING SLAB

Application filed November 26, 1928. Serial No. 322,029.

My invention relates to building slabs designed to cover old weather boarding, bricks, sheathing, etc., of a building so that on completion the outer face of the building will appear as though constructed of marble, stone, tile, etc.

Another object is to provide an economical and durable slab made of plastic material which can be molded in any suitable design and affixed as a veneer to a building.

A further object is to provide water-proof slabs with tight joints so that when applied to a building moisture cannot seep through the slabs or pass through the joints between said slabs.

Another object is to provide a slab with an embedded reinforcement which not only strengthens said slab but affords means whereby it may be secured to a building with screws, nails or other suitable fastening devices.

In order that the invention may be fully understood reference will now be had to the accompanying drawings, in which:

Fig. 1 is a front elevation of a portion of a building partly covered with the slabs.

Fig. 2 is a detail perspective view looking at the rear of a reinforcing member which is embedded in the plastic material from which the slab is formed.

Fig. 3 is a detail perspective view looking at the rear of a finished slab.

Fig. 4 is an enlarged broken vertical section on line 4—4 of Fig. 1.

Fig. 5 is an enlarged broken horizontal section on line 5—5 of Fig. 1.

Fig. 6 is a detail perspective view of one of a number of slabs for application to the corners of a building.

Referring in detail to the different parts, A represents the outer surface of the building to which wooden or other suitable strips 2 are nailed or otherwise secured.

4 designates the slab as a whole which is reinforced with a member 6 embedded in the plastic material forming the main portion of said slab. The reinforcing member 6 consists of a hollow rectangular frame 8 and woven wire 10, which latter is suitably se-

cured to said frame and covers the large opening therein as shown by Fig. 2.

The frame 8 consists preferably of galvanized sheet metal and the outer portions of its vertical sides are folded to provide vertical grooves 14 and flanges 15, which latter form the rear sides of the former and reinforce said frame 8.

The outer portion of the horizontal upper part of the frame 8 is folded to provide a horizontal groove 18 and a longitudinal tongue 20, while the lower horizontal portion of said frame 8 is folded to provide longitudinal grooves and tongues 26 and 28, respectively.

In the manufacture of the slab the plastic material is forced through the openings in the woven wire 10 and also through perforations 30 formed in the frame 8 and is struck off flush, or substantially flush, with the rear surfaces of the flanges 15 and the tongues 20 and 28. Sufficient plastic material is em-

ployed to give the desired thickness to the slab, the margins of which have longitudinal grooves 34 for a purpose hereinafter de-

scribed. The upper and lower margins 36 and 38, respectively, of the plastic material are sloped downwardly towards the front surface of the slab for the purpose of shed-

ding any rain which may enter the joints between said slabs when the latter are secured to the building. The plastic material may have suitable waterproof material intermixed therewith or the rear surface only may be coated with a waterproof material for pre-

venting moisture from penetrating through to the strips 2 and the building. The faces of the slabs, during the course of manufacture, may be rendered highly attractive by embedding therein broken or crushed glass, shells, stone, etc., or said faces may be treated with a single color or a plurality of colors so that the finished structure may have a very ornate appearance.

The slabs 4 are preferably constructed in corner sections 40, half sections 42 and full or square sections 44, so that they may be laid in break joint fashion as shown by Fig. 1. Preparatory to applying the slabs, the strips 2 are nailed to the outer surface

of the building and so spaced that a full sized slab will reach across one strip and half way across two others disposed at opposite sides of the first-mentioned strip. The 5 slabs are then laid in super-imposed tiers and secured to the strips 2 with suitable means such as screws, nails, or other fastening devices 45, which pass through holes 46 in the upper portions of the tongues 20. 10 As one tier of slabs is laid upon another the tongues 28, which register with the spaces between the strips 2, are slipped over and behind the tongues 20 which latter enter the grooves 26 and coat with said tongues 28 in firmly locking the abutting upper and 15 lower ends of the slabs together. Before placing each slab in place the marginal grooves 34 are filled with a waterproof putty or other suitable substance 48, and before 20 one tier of slabs is placed upon another the vertical joints between the slabs are further rendered water-tight by slipping weather strips 50 down through the ends of the 25 grooves 18 and into the grooves 14 at the abutting sides of the slabs. The weather strips 50 also assist in holding the slabs in proper relation to each other.

From the foregoing description it is apparent that I have provided slabs embodying the advantages above pointed out, and 30 while I have shown and described one form of the invention I reserve all rights to such other forms and modifications thereof as properly fall within the spirit and scope of 35 the invention as claimed.

Having thus described my invention, what I claim and desire to secure by Letters Patent, is:

1. In combination with a plurality of 40 strips spaced equal distances apart and arranged perpendicularly upon the wall of a building, a plurality of slabs secured to said strips and each consisting of a plastic body, a reinforcing member embedded in each 45 body, a tongue extending longitudinally of the upper portion of each reinforcing member, and a tongue and groove at the lower portion of each reinforcing member, the last-mentioned tongue fitting between two 50 of the strips while said groove receives the tongue at the upper portion of an underlying reinforcing member.

2. In combination with a plurality of 55 strips spaced equal distances apart and arranged perpendicularly upon the wall of a building, a plurality of slabs secured to said strips and each consisting of a plastic body having a continuous groove extending around its margins and each slab being 60 wide enough to bridge two spaces between the strips, a reinforcing member embedded in each body, a tongue extending longitudinally of the upper portion of each reinforcing member, and a plurality of tongues 65 at the lower portion of each reinforcing

member which are spaced apart to enter the spaces bridged by the slab, the last-mentioned tongues being shaped to form grooves for the reception of the tongue at the upper portion of the underlying reinforcing member. 70

In testimony whereof I affix my signature.
JOHN H. POWERS.
